United States Patent

Des. 235,977

Patented July 22, 1975

235,977

REFLECTOR

Gerald Golden, Highland Park, Ill., assignor to
Beatrice Foods Co., Elgin, Ill.

Filed Apr. 16, 1974, Ser. No. 461,374

Term of patent 14 years

Int. Cl. D10—06

U.S. Cl. D10—111

FIG. 1 is a front elevational view of a reflector embodying the design;

FIG. 2 is a rear elevational view of the reflector embodying the design;

FIG. 3 is a top plan view of the reflector illustrated in FIGS. 1 and 2;

FIG. 4 is a bottom plan view of the reflector shown in FIGS. 1 and 2; and

FIG. 5 is a side elevational view of the reflector illustrated in FIGS. 1 and 2.

The oblique line shading indicates a reflective surface.

I claim:

The ornamental design for a reflector, substantially as shown and described.
